UNITED STATES PATENT OFFICE.

SETH BOYDEN, OF NEWARK, NEW JERSEY.

MACHINERY FOR FORMING HAT-BODIES.

Specification of Letters Patent No. 22,698, dated January 25, 1859.

To all whom it may concern:

Be it known that I, SETH BOYDEN, of Newark, in the county of Essex and State of New Jersey, have invented a new and useful Improvement in Machinery for Forming Hat-Bodies; and I do hereby declare that the following is a full, clear, and exact description of the same, reference being had to the annexed drawings, making a part of this specification, in which—

Figure 1, is a longitudinal vertical section of my invention taken in the line α , α , Fig. 2. Fig. 2, a plan or top view of ditto. Fig. 3, a detached side sectional view of one of the tubes and joint connections.

Similar letters of reference indicate corresponding parts in the two figures.

This invention relates to a novel means employed for conveying the fur from the picker to the cone on which the hat body is formed as hereinafter fully shown and described, whereby an exceedingly simple and efficient machine is obtained and one capable of forming the body of varying thickness as may be desired.

The invention consists in having steam pipes provided with adjustable tubes and placed in such relation with the picker and cone, that the steam will convey the fur from the picker to the cone and deposit the fur on the same in a proper state favorable to the expeditious and proper forming of the hat body.

To enable those skilled in the art to fully understand and construct my invention I will proceed to describe it.

A, represents a frame on the upper part of which a picker B, is placed and also an endless apron C. The picker has its upper surface covered by a cap a , and a roller b , is placed directly over and in the same plane with the inner roller of the apron C.

D, is a vertical shaft or arbor placed in one end of the frame A, and having an annular horizontal plate c , on its upper end. On the plate c , the perforated cone E, is placed and a suction pipe F, is placed below the plate c , and cone E.

The above parts are constructed in the usual way and therefore do not require a more minute description.

Within the frame A, and at each side, a pipe G, is placed. These pipes communicate at their lower ends with a steam boiler, and their upper parts pass upward, one at each side of the picker, and in line with its

front side, the pipes G, extending upward as high as the cone E, as shown clearly in Fig. 1.

To each pipe G, above the frame A, a series of horizontal tubes d , are attached, one above the other and extending to the tops of the pipes. These tubes d , are not rigidly attached to the pipes G, G, but are connected to them by joints, so that the tubes may be adjusted to a certain degree in any direction.

By referring to Fig. 3, the manner of attaching the tubes to the pipes will be clearly seen. The pipes G, are provided with horizontal projections e , which have screw threads cut on them and on which caps f , are secured, one cap on each projection. The inner end of each tube d , terminates in a sphere or ball g , and these spheres or balls are fitted in corresponding cavities h , within the caps and projections. By unscrewing the caps f , the spheres g , may be turned in their sockets and the tubes d , adjusted as desired and the tubes may be secured in any desired position within the range of their movement or adjustability by screwing up the caps f .

The operation is as follows:—Motion is given the endless apron C, picker B, and arbor D, in any proper way. The cone E, is placed on the plate c , and the fur is placed by the operator on the apron C. This apron as usual conveys the fur to the picker B, which by a rapid rotation throws the fur outward so that the steam which issues from the tubes d , will convey it to the cone E, the tubes being so adjusted as to give the jet of steam the proper direction. The fur is knit on the cone by atmospheric pressure induced by a suction in the pipe F, below the cone, the suction being caused by a fan as usual. The fur may be conveyed to the cone in greater or less quantities at different points, so that the hat body will vary in thickness by adjusting the tubes d . Hat bodies most generally gradually increase in thickness from the crown to the brim, and in order to effect this result by my invention the tubes d , are so adjusted as to be gradually more inclined from the upper to the lower one, thereby conveying the fur to the cone in a gradually increasing volume from its upper to its lower end, (see red lines Fig. 1,) or at any desirable point the operator wishes to arrest the fur.

I do not claim the endless apron C, picker

B, and rotating perforated cone E, for these have been long known and used in machines for forming hat bodies, but

Having thus described my invention, what I do claim as new and desire to secure by Letters Patent, is,

Conveying the fur from the picker B, to the perforated cone E, by means of jets of

steam issuing from tubes *d*, arranged relatively with the picker B, and cone E, substantially as described to effect the desired purpose. 10

SETH BOYDEN.
